UNITED STATES PATENT OFFICE.

DELAVERGNE P. WILLIAMS AND JOHN F. WILLIAMS, OF SANDUSKY, OHIO.

PLUG-IN ATTACHMENT.

1,417,649.

Specification of Letters Patent. Patented May 30, 1922.

Application filed May 21, 1921. Serial No. 471,416.

To all whom it may concern:

Be it known that we, DELAVERGNE P. WILLIAMS and JOHN F. WILLIAMS, citizens of the United States, residing at Sandusky, in the county of Erie, and State of Ohio, have invented a certain new and useful Improvement in Plug-In Attachments, of which the following is a full, clear, and exact description, reference being had to the accompanying drawings.

This invention relates to electrical plug-in attachments which while capable of many uses are directed particularly for use in radio circuits.

Some of the objects of the present invention are to provide a combined plug and condenser which shall be particularly useful in radio circuits where it is often desirable to plug the head receivers or other apparatus in the circuit at various stages of amplification or at different points in the circuit; to provide a device of the aforesaid character which shall be simple in construction and inexpensive to manufacture, while further objects and advantages will appear as the description proceeds.

In the accompanying drawing wherein we have shown certain forms of our invention Fig. 1 is a vertical sectional view of a combined plug and condenser; Fig. 2 is a similar view of a modified form of combined plug and condenser wherein the condenser is of the variable type; Fig. 3 is an end elevation thereof; Fig. 4 is a vertical sectional view of a combined plug, condenser and telephone receiver, and Fig. 5 is a similar view of a modified form wherein the plug and condenser are detachably connected to the receiver.

Describing by reference characters the various parts illustrated and referring particularly to Fig. 1, 10 indicates the metallic body portion of the plug which is reduced in diameter at one end thereof as indicated at 11 to form one contact surface. The other contact is formed by a rod 12 disposed within an insulating sleeve 13 which is fitted into a bore 14 extending through the contact 11.

The body portion 10 of the plug is cut away as indicated at 16 to form a recess therein for a small condenser indicated at 17 and also to permit the lead in wires 18 to be connected to the condenser and contacts. The condenser 17 is usually of small capacity and may be formed from a plurality of al-

ternate sheets of a conductor and a suitable dielectric laid, one upon the other and each of a size to fit in said recess or may be formed of a plurality of larger sheets of a dielectric and a conductor which are rolled and pressed to the shape of said recess. The lead in wires 18 are connected to the contacts 11 and 12 and the terminals of the condenser are shunted across these contacts which is the usual connection for use in radio circuits when the plug is attached to the end of the telephone cord. A suitable sleeve 19 formed from insulating material is fitted over the body portion 10 and closes the recess 16.

In Fig. 2 we have shown a modified form of combined plug and condenser wherein the condenser is of the variable type. In this view 20 indicates a receptacle preferably formed of insulating material and provided with a removable cover 21 and a sleeve 22 projecting from the opposite side of said receptacle. A metallic sleeve 23 is fitted over the sleeve 22 and forms one contact and a rod 24 disposed within the sleeve 22 serves as the other contact. The variable condenser 25 indicated at 25 may be of a type which is formed by taking off taps at various points of a fixed condenser and connecting said taps to suitable contacts 26 which are mounted on the cover 21. A fan blade switch 27 is mounted on the cover and by rotating the handle 28, said switch will contact with any or all of the contacts and thereby vary the capacity in the circuit.

In Fig. 4 we have shown a combined receiver, condenser and plug. In this form the receiver shell 30 is formed with a projection 31 to house the condenser 32 and a still further projection 33 of said insulating material serves to separate the contacts 34 and 35. The telephone is connected to the aforesaid contacts and the condenser is shunted thereacross. A device of this type is particularly compact and useful as a loud speaker for radio circuits and may be easily inserted in the circuit at any desired point where the head receivers would ordinarily be plugged in.

In Fig. 5 we have shown a modified form of combined receiver, condenser and plug wherein the housing 31^a is detachably connected to the receiver shell 30^a in any suitable manner, as by means of the bayonet type of joint indicated at 37. The condenser 32^a and contacts 34^a and 35^a are each connected 110

to the spring pressed pins 38 and said pins contact with stationary pins 39 which in turn are connected to the terminals of the telephone receiver. With this arrangement 5 the receiver may be used as a loud speaker or may be detached from the plug and condenser and used with a head band in the ordinary manner.

Having thus described our invention, 10 what we claim is:

1. The combination with a plug comprising a body portion having a pair of contacts projecting therefrom, of a condenser arranged within said body portion and in electrical circuit with said contacts. 15
2. The combination with a plug comprising a body portion having a pair of contacts projecting therefrom, of a condenser carried by said body portion and in electrical circuit with said contacts. 20
3. The combination with a plug comprising a body portion having a pair of contacts projecting therefrom, of a condenser arranged within said body portion and shunted across said contacts. 25
4. The combination with a plug comprising a body portion having a pair of contacts projecting therefrom, of a condenser arranged within said body portion and in electrical circuit with said contacts and an electrical instrument mounted on the body portion of said plug and in electrical circuit with said contacts and condenser. 30

5. The combination with a plug comprising a body portion having a pair of contacts 35 projecting therefrom, of an electrical instrument mounted on the body portion of said plug and in electrical circuit with said contacts.

6. The combination with a plug comprising a body portion having a pair of contacts projecting therefrom, a condenser arranged in said body portion and in electrical circuit with said contacts, and a telephone receiver mounted on said body portion and in electrical circuit with said contacts and condenser. 40 45

7. The combination with a plug comprising a body portion having a pair of contacts projecting therefrom, a condenser arranged 50 in said body portion and in electrical circuit with said contacts and an electrical instrument detachably connected to said body portion and adapted to be electrically connected with said contacts. 55

8. The combination with a plug comprising a body portion having a pair of contacts projecting therefrom, of an electrical instrument detachably connected to said portion and adapted to be connected in electrical circuit with said contacts. 60

In testimony whereof, we hereunto affix our signatures.

DELAVERGNE P. WILLIAMS.
JOHN F. WILLIAMS.
